P. TROSKI

RAIL CONNECTER

Filed Nov. 26, 1926

Inventor

Peter Troski

By Attorney

Marvin Deems

UNITED STATES PATENT OFFICE.

PETER TROSKI, OF ARISTA, WEST VIRGINIA.

RAIL CONNECTER.

Application filed November 26, 1926. Serial No. 150,642.

This invention relates to connectors and more particularly to joints for railway tracks.

It is a well known fact that altogether too often accidents occur due to faulty rail connections, resulting in great losses of life and property.

It is therefore the object of this invention to provide a device for positively and 10 securely fastening together the ends of rails so as to withstand the shocks and terrific vibrations to which such rails are subjected.

This and other important objects are accomplished by the unique combination, arrangement and construction of elements hereinafter described and delineated in the 15 accompanying illustration, in which:—

Figure 1 is a general top plan view of a conventional track embodying therein a joint 20 made in accordance with the invention.

Figure 2 is a side elevational view of the same.

Figure 3 is a transverse sectional view taken on line 3—3 of Figure 1.

Figure 4 is a like view taken on line 25 4—4 of Figure 1.

In the drawing, the numeral 10 designates a tie on which rests the base 11 of a rail 12, the base being held securely thereto by clamp 30 plates 14 riveted to the tie, as at 15, all of the foregoing being well known.

The invention consists of a rectangular plate 16 on which rests the base 11 of the rail 12, the ends of which abut each other at 35 17, midway the length of the plate 16.

On one side of the rail at the ends of the plate 16 are secured by rivets 18, a pair of clamp plates 19 holding the base 11 securely to the plate 16.

The main fastening element consists of a 40 base 20 engaging the base 11, of the rail 12, from which rises a vertical stem portion 21 fitting intermediate the base 11 and the head 22 of the rail, the same being in close relation to the stem 23 of the rail. 45

The base 20 contains a plurality of recesses 24 in which fit rivets 25 by which the device is fixed to the plate 16.

Thus, it may be seen that a joint has been disclosed for securing into proper fixed position, the ends of rails, so as to avoid loosening by the shocks and vibrations of passing trains. 50

Although the foregoing is descriptive of the preferred embodiment of my invention, 55 it is not desired that the same be interpreted in a limiting sense, as changes in construction may be made without departing from the scope of the claim hereto appended.

Having thus described my invention, what 60 I claim as new and desire to secure by Letters Patent, is:—

A rail connector comprising a rectangular plate, said plate supporting the base of a rail, short rectangular clamps at the ends of 65 said plate engaging one side of the rail base, a recessed elongated base element engaging the other side of the rail base, said base element being fixed to said plate, and a stem portion on said base element engaging 70 the stem of the rail intermediate the base and head thereof.

In witness whereof I have affixed my signature.

PETER TROSKI.
